CLAIM

The ornamental design for a fluorescent lamp holder, as shown and described.

DESCRIPTION

FIG. 1 is a top, front and left-side perspective view of a fluorescent lamp holder showing our new design;

FIG. 2 is a front elevational view thereof, the rear elevational view being identical;

FIG. 3 is a left-side elevational view thereof, the right-side elevational view being identical;

FIG. 4 is a top plan view thereof;

FIG. 5 is a bottom plan view thereof;

FIG. 6 is a top, front and left side perspective view of a second embodiment of our new design;

FIG. 7 is a front elevational view thereof, the rear elevational view being identical;

FIG. 8 is a left-side elevational view thereof, the right-side elevational view being identical;

FIG. 9 is a top plan view thereof; and

FIG. 10 is a bottom plan view thereof.

FIG. 1.

FIG. 2.

FIG. 3.

FIG. 4.

FIG. 5.

FIG. 6.

FIG. 7.

FIG. 8.

FIG. 9.

FIG. 10.
